UNITED STATES PATENT OFFICE.

JACOB B. CONOVER, OF JERSEY CITY, NEW JERSEY.

CAN-COVER.

981,384.

Specification of Letters Patent. Patented Jan. 10, 1911.

Application filed November 18, 1910. Serial No. 592,963.

To all whom it may concern:

Be it known that I, JACOB B. CONOVER, a citizen of the United States of America, residing at Jersey City, in the county of Hudson and State of New Jersey, have invented 5 certain new and useful Improvements in Can-Covers, of which the following is a specification, reference being had therein to the accompanying drawings, forming part 10 thereof.

My invention relates to covers for cans and particularly for milk cans.

One object of my invention is the strengthening and stiffening of such covers by the 15 mutually reinforcing action of double walls, particularly in the flange and neck portions thereof.

Another object of my invention is the 20 elimination of unsanitary joints, gaps or crevices.

Further objects are durability and facility of manufacture.

Still other objects and advantages of my 25 invention will appear from the following description.

I shall now describe the embodiments of my invention shown in the accompanying drawing, and shall thereafter point out my invention in claims.

30 Figure 1 is a central sectional elevation of my improved cover. Fig. 2 is a similar view, on a reduced scale, of a cover of modified form in place on a milk can, the lower part of the can being broken away.

35 The cover is composed of two seamless pieces, both of suitable sheet material, as tinned iron. The lower piece has an outwardly extending and downwardly curved top flange or rim *c* and a stopper portion. 40 The stopper portion has a downwardly extending neck *d* of nearly cylindrical form, but slightly smaller in diameter toward its lower end to insure a tight fit in the neck of the milk can, the neck of the cover having 45 double walls formed by folding the metal back upon itself. As shown in Fig. 1, the double walls are continued throughout the neck. As shown in Fig. 2, the double walls are continued throughout the portion of the 50 neck which engages the neck of the can. As shown in Fig. 1, the stopper portion is completed by a flat or disk shaped inner top portion *a*. As shown in Fig. 2, the stopper

portion is completed by an arched inner top portion *a'* which braces and reinforces the 55 neck at its point of departure therefrom and braces and reinforces the upper top portion of the cover at central portions thereof. The double walls of the neck of the cover are sufficiently close together to 60 reinforce each other, as shown in Fig. 1, and may in some instances be in contact. As shown in Fig. 2, they are in contact at the top of the double portion of the neck. The upper piece *b* of the cover is shaped to fit 65 over the lower piece in such close proximity thereto as to reinforce the flange portion *c* and the disk portion *b* thereof, as shown in Fig. 1, or may be in actual contact therewith, or may be in close proximity to the 70 lower piece at the flange portion thereof and again in close proximity and actual contact therewith at central portions thereof, as shown in Fig. 2, and provides a smooth top 75 without any angular bends, which is reinforced by the lower piece throughout its entire surface, as shown in Fig. 1, and is reinforced by the lower piece at the flange, where it is subjected to the greatest strains, and at central portions, where its own resisting power is at a minimum, as shown in Fig. 2. The upper and lower pieces of the 80 cover are secured together at their margins by beading them upward around a reinforcing hoop or wire *g*, the lower piece being of larger diameter than the upper piece at its outer periphery so as to extend over 85 into contact with the top surface of the upper piece after it has passed over the wire, thus closing the usual gap at the beading 90 and providing a continuous smoothly rounded surface and a single joint, and this joint may be closed by soldering or tinning and is at the upper and outer part of the cover so that it may be readily observed and easily 95 cleaned.

The can shown, having a breast *f*, double neck *h* and bowl *e*, is of the well known New York type. As usual, there is considerable clearance between the top of the neck of the can and the top of the cover, to accommodate the bowl of the can. The cover, as usual, extends over and beyond the bowl of the can.

In the daily rough handling of milk cans, 105 the covers are subjected to violent shocks

and strains. For example, the removal of a cover from its tight fit in the can neck, is frequently accomplished by hammering upward against the outer margin of the flange 5 of the cover. Even if this is not necessary, the removal of the cover is accomplished by grasping the flange of the cover and twisting the cover until it is released. Frequently the cover is first twisted in this manner, and this failing to release it, is then hammered loose. The resulting very heavy 10 shocks and stresses tend to distort the cover, and if the cover becomes distorted so that it will not tightly fit the can neck, it is useless. Breakages also frequently occur in 15 covers as heretofore made, because of this rough handling and violent usage. The outer flange of the cover is one of the handiest places to grasp in moving a can about 20 and is frequently grasped in handling the can to the detriment of the cover as heretofore made. Cans are frequently stacked one on top of another while traveling in a 25 freight car or wagon, and here the cover of the lower can must sustain the weight of the can above it and receive the shocks that result from the vibrations of the car or wagon. The construction of my can cover adapts it 30 to resist all of this rough usage. Each wall is reinforced by an adjacent wall, either throughout its entire surface or at the portions where such reinforcement is most needed. The peripheral strains and shocks 35 imparted to the flange of the cover are resisted both by the smooth upper piece, strengthened by the arched form of its outer part, and by the lower piece similarly arched at its outer part and reinforced at this outer part by the upper piece. The great strength 40 of this flange is of prime importance in preserving the shape of the cover. This reinforcement of one part by the other continues at what has heretofore been a usual point of breakage, the upper end of the neck of the 45 cover, and is continued between the inner top portion of the lower piece and the flat part of the upper piece which is above it, either throughout such flat part of the upper piece or at the central and weaker parts 50 thereof. The arched form of the inner top portion shown in Fig. 2, gives to this portion great rigidity of structure.

The two pieces of stock from which the cover is made, are drawn by dies and may be 55 finished by spinning. The two pieces are then put together and their peripheral edges united by beading in the manner above described. After they have been secured together, they may be further finished by spinning. It will be observed that there is no 60 exposed gap in any part of the cover, and only one joint, and that joint thoroughly sanitary, while all the bends, whether convex or concave, are smoothly rounded, so 65 that there are no sharp corners or gaps or

crevices within which "particles of milk or dirt may lodge, and every part of the cover may be easily and thoroughly cleaned.

It is obvious that various modifications may be made in the construction shown and above particularly described within the principle and scope of my invention.

I claim:

1. A can cover comprising a lower piece shaped to form a stopper portion and an upper projecting flange, the stopper portion consisting of a double walled neck portion and an inner top portion; and an upper piece covering the lower piece and including a projecting flange and a top for the stopper portion, the two pieces being joined at their margins. 75

2. A can cover comprising a lower piece shaped to form a stopper portion and an upper projecting flange, the stopper portion 80 consisting of a double walled neck portion and an inner top portion; and an upper piece including a projecting flange and a top for the stopper portion and disposed over the lower piece so as to be reinforced 90 by the flange and the inner top portion of the lower piece. 85

3. A can cover comprising a lower piece shaped to form an outwardly extending and downwardly curved flange and a stopper portion, the stopper portion consisting of a double walled neck portion and an inner top portion; and an upper piece having a correspondingly shaped flange and a top for the stopper portion and disposed over the lower piece so as to be reinforced by the flange and the inner top portion of the lower piece, the upper and lower pieces being 95 joined at their margins. 100

4. A can cover comprising a lower piece 105 shaped to form a stopper portion and an upper projecting flange, the stopper portion consisting of a double walled neck portion and an inner top portion of arched form; and an upper piece covering the lower piece 110 and including a projecting flange and a top for the stopper portion, the two pieces being joined at their margins. 115

5. A can cover comprising a lower piece shaped to form a stopper portion and an upper projecting flange, the stopper portion 120 consisting of a double walled neck portion and an inner top portion of arched form; and an upper piece including a projecting flange and a top for the stopper portion and disposed over the lower piece so as to be reinforced by the flange and the arched inner top portion of the lower piece. 125

6. A can cover comprising a lower piece shaped to form an outwardly extending and downwardly curved flange and a stopper portion, the stopper portion consisting of a double walled neck portion and an inner top portion of arched form; and an upper piece 130 having a correspondingly shaped flange and

a top for the stopper portion and disposed over the lower piece so as to be reinforced by the flange and the arched inner top portion of the lower piece, the upper and lower pieces being joined at their margins.

5 7. A can cover of sheet material having a marginal beaded joint comprising a reinforcing hoop over which the sheet material is bent, the sheet material extending around 10 the reinforcing hoop and inward beyond the hoop, so as to bridge the gap between the hoop and the sheet material, and into face contact with the adjacent surface of the sheet material.

15 8. A can cover comprising two pieces of sheet material, an upper piece and a lower piece, joined at their outer margins by a beaded joint including a reinforcing hoop, one piece extending around the reinforcing 20 hoop and inward beyond the hoop, so as to bridge the gap between the hoop and the sheet material, and into face contact with the surface of the other piece.

9. A can cover comprising a lower piece shaped to form a stopper portion and an upper projecting flange, the stopper portion consisting of a double walled neck portion and an inner top portion; and an upper piece including a projecting flange and a top for the stopper portion and disposed over the lower piece so as to be reinforced by the same; the two pieces being joined at their margins by a beaded joint including a reinforcing hoop, the lower piece extending upward and around the reinforcing hoop 35 and inward beyond the hoop, so as to bridge the gap between the hoop and the upper piece, and into face contact with the upper piece.

In testimony whereof I have affixed my 40 signature in presence of two witnesses.

JACOB B. CONOVER.
